DESIGN FOR A NOVELTY MINIATURE BAR

David W. Dunberg, New York, N. Y.

Application July 13, 1940, Serial No. 93,629

Term of patent 7 years

To all whom it may concern:

Be it known that I, David W. Dunberg, a citizen of the United States of America, residing in New York, county of New York and State of New York, have invented a new, original, and ornamental Design for a Novelty Miniature Bar, of which the following is a specification, reference being had to the accompanying drawing, forming part thereof.

Fig. 1 is a front perspective view of a novelty miniature bar, showing my new design.

Fig. 2 is a rear perspective view thereof.

Fig. 3 is an end elevational view.

Fig. 4 is a top plan view.

I claim:

The ornamental design for a novelty miniature bar, as shown.

DAVID W. DUNBERG.
